UNITED STATES PATENT OFFICE.

ELVAH O. BULMAN, OF GRAND RAPIDS, MICHIGAN.

PUZZLE.

1,146,844.

Specification of Letters Patent. Patented July 20, 1915.

Application filed May 20, 1914. Serial No. 839,688.

To all whom it may concern:

Be it known that I, ELVAH O. BULMAN, a citizen of the United States, residing at Grand Rapids, in the county of Kent and State of Michigan, have invented new and useful Improvements in Puzzles, of which the following is a specification.

My present invention relates to puzzles, and its object is to provide a new, useful and interesting puzzle and apparatus therefore.

This object is attained by, and my invention finds a preferable embodiment in, the apparatus hereinafter described and illustrated in the accompanying drawings, in which:—

Figure 1 is a plan view of such apparatus; and Fig. 2 is a vertical section of the same on line A—A of Fig. 1.

I provide a suitable board 1, on which are displayed a central marked position 2 and a number of marked positions on each side thereof. In the form illustrated there are three positions numbered respectively 3, 4, 5 and 5, extending from one side of the central position 2, and a like number, 6, 7 and 8, extending from the other side of the said central position. These various marked positions, in the form illustrated, are disposed in a straight line, but they may be arranged in any desired direction or line.

The positions on one side of the central position are preferably distinguished from those on the other side, as by suitable coloring; for instance, those on the right hand side may be colored red, and those on the left hand side may be colored black.

I provide as many playing pieces as there are side positions, such pieces 9, 10 and 11 being distinguished (as by coloring corresponding to that of the side position 3, 4 and 5 on one side) from the other playing pieces 12, 13 and 14 which may be colored correspondingly to the other side positions 6, 7 and 8. The red pieces 9, 10 and 11 are placed upon the red side positions 3, 4 and 5, and the black pieces 12, 13 and 14 are placed on the black side positions 6, 7 and 8, the puzzle being to move such pieces so that all the red pieces may occupy the black positions and all the black pieces the red positions, moving only one piece at a time, jumping only one piece at a time.

The puzzle is solved by the following moves in the following order: From position 3 to central position 2: from position 8 to position 3: from position 7 to position 8: from central position 2 to position 7: from position 4 to central position 2: from position 5 to position 4: from position 3 to position 5; from position 8 to position 3; from position 6 to position 8: from position 7 to position 6: from central position 2 to position 7: from position 4 to central position 2: from position 3 to position 4: from position 8 to position 3: from central position 2 to position 8.

Preferably the board 1 is formed of heavy paper or cardboard with portions 15 and 16 at the ends, such cardboard being perforated, as at 18, to permit the ready separation of the portions 15 and 16 from the body of the board 1. Preferably the board 1 is cut through with dies in such manner as to form the playing pieces (as shown in 75 the portions 15 and 16 at each end of the board 1,), the cutting edges of the dies however being interrupted at one or more points, as 19, so that the board is not cut at such points: the playing pieces, however, 80 may be readily detached from the board by breaking or tearing the paper at these points 19.

Not confining myself to details of construction shown or described, I claim:—

1. An apparatus for a puzzle comprising a board displaying a central marked position, and two series each of three marked side positions, extending from said central position, and playing pieces corresponding 90 in number to the side positions and distinguishingly divided into two divisions.

2. In apparatus of the character described, a board cut through to form the periphery of a playing piece, the cutting being interrupted in a portion of such periphery, whereby the playing piece is adapted to be readily detached from the board by breaking off said interrupted portion.

In testimony whereof I have hereunto set 100 my hand in presence of two subscribing witnesses.

ELVAH O. BULMAN.
